US00D981526S

(12) **United States Design Patent** (10) **Patent No.:** **US D981,526 S**
(45) **Date of Patent:** **** Mar. 21, 2023**

(54) **ELECTRIC MOSQUITO SWATTER**

(71) Applicant: **Foshan Shunde Lexueer Electric Co., Ltd.**, Guangdong Province (CN)

(72) Inventor: **Baozhu Liao**, Guangdong Province (CN)

(**) Term: **15 Years**

(21) Appl. No.: **29/773,638**

(22) Filed: **Mar. 10, 2021**

(30) **Foreign Application Priority Data**

Sep. 11, 2020 (CN) 202030537636.6

(51) **LOC (14) Cl.** **22-06**
